UNITED STATES PATENT OFFICE

161,145

CABINET FOR A HEATER OR THE LIKE

Lawrence H. Wilson, Detroit, Mich., assignor to
Motor Wheel Corporation, Lansing, Mich., a
corporation of Michigan

Application March 1, 1950, Serial No. 8,229

Term of patent 14 years

(Cl. D81—19)

To all whom it may concern:

Be it known that I, Lawrence H. Wilson, a citizen of the United States, residing at Detroit, in the county of Wayne and State of Michigan, have invented a new, original, and ornamental Design for a Cabinet for a Heater or the like, of which the following is a specification, reference being made to the accompanying drawing, forming part thereof.

Fig. 1 is a perspective view of a cabinet for a heater or the like, showing my new design.

Figs. 2, 3 and 4 are sections along the lines 2—2, 3—3 and 4—4 respectively of Fig. 1.

The side of the cabinet not shown is the same as the side shown except that the side of the cabinet not shown does not have a door therein, and the back of the cabinet is plain.

I claim:

The ornamental design for a cabinet for a heater or the like, substantially as shown and described.

LAWRENCE H. WILSON.
